UNITED STATES PATENT OFFICE.

HERMAN B. COLLINS, OF FULTON, NEW YORK.

FAN.

SPECIFICATION forming part of Letters Patent No. 591,033, dated October 5, 1897.

Application filed June 9, 1896. Serial No. 594,851. (No model.)

To all whom it may concern:

Be it known that I, HERMAN B. COLLINS, of Fulton, in the county of Oswego, in the State of New York, have invented new and useful Improvements in Fans, of which the following, taken in connection with the accompanying drawings, is a full, clear, and exact description.

My invention relates to improvements in fans particularly applicable for ventilating purposes, and has for its object the production of a device for controlling the operation of a fan which is compact, simple in construction, consists of a minimum number of parts, and is highly effective and durable in use; and to this end it consists, essentially, in the construction and arrangement of the parts for adjusting the fan-blades and controlling the operation of the means for revolving said blades, all as hereinafter fully described, and pointed out in the claims.

In describing this invention, reference is had to the accompanying drawings, forming a part of this specification, in which like letters of reference indicate corresponding parts in all the views.

Figure 1 is a longitudinal vertical section, partly in elevation, of a fan embodying my invention and the means for revolving said fan. Fig. 2 is a vertical section taken on line 2 2, Fig. 1; and Fig. 3 is a horizontal section taken on line 3 3, Fig. 1.

A represents a revoluble supporting-frame, B fan-blades secured to said frame, and C an actuating part for adjusting the fan-blades. The frame A is driven by any suitable mechanism, and the operation of said mechanism is controlled by an actuating part a of any suitable construction. The mechanism for driving the frame A preferably consists of a motor a', supported within a frame or casing A' and having its armature fixed to the upper end of a revoluble upright shaft A². A driver A³ encircles the shaft A² and is formed with a conical face engaged with rollers A⁴, which revolve around a circular track A⁵, provided upon the frame or casing A'. The rollers A⁵ are suitably supported upon a head which is provided upon the upper end of a revoluble shaft A⁶, journaled in the frame or casing A. The lower end of the shaft A⁶ is suitably fixed to the revoluble supporting-

frame A'. The motor a' is electrically connected to a switch a², which governs the passage of the current and is preferably provided with suitably-fixed terminals A⁷ and a movable member A⁸, carrying terminals movable into and out of contact with the former terminals, which are connected in circuit with one of the electric conductors or wires leading to said motor. The movable member A⁸ is usually actuated by a rocking lever A⁹, which is normally elevated by a suitable spring, Fig. 1, and is provided with a ratchet or pawl for engaging ratchet-teeth upon said member. A suitable connection A¹⁰ is secured to one end of the lever A⁹ and to a sleeve A¹¹, which encircles the shaft A⁶ and is movable lengthwise thereof. The lower end of said shaft is formed with a lengthwise chamber, and arranged in said chamber is a reciprocating rod having its upper end connected to substantially horizontal pins projecting into a groove in the inner face of the sleeve A¹¹. A spring A¹² encircles the reciprocating rod for normally elevating the same, and the lower end of said rod is connected to the actuating part a, which is preferably movable in a passage c, extending longitudinally through the actuating part C, presently described, and extends beneath said actuating part C for facilitating engagement therewith.

The revoluble frame A is provided with a central aperture a³, a guide a⁴, extending downwardly from the aperture, and substantially parallel bearings a⁵, extending from opposite sides of said aperture. The fan-blades are preferably disposed in substantially parallel planes, and their adjacent ends are provided with spindles or shanks b, journaled in the bearings a⁵. The adjacent sides of the free extremities of the spindles or shanks b are provided with laterally-extending arms or projections b', arranged opposite to each other and formed with grooves b², which are preferably formed rounding in cross-section and extend outwardly from the axis of said spindles or shanks.

The actuating part C is arranged at substantially right angles with the fan-blades B and preferably consists of a hollow rod reciprocally movable in the guide a⁴. The upper end of said actuating part is formed with a substantially spherical projection c', hav-

ing its opposite faces movable in the grooves b^2 . The arms or projections b' , provided with the grooves b^3 , are yieldingly forced endwise toward said projection c' by springs b^3 , which 5 also prevent rattling of the parts. These springs preferably encircle the spindles or shanks b and are interposed between shoulders b^4 a^6 , formed, respectively, upon said spindles or shanks and the frame A. The 10 lower end of the actuating part is provided with a suitable handpiece b^5 , here shown as formed with an oil-receiving chamber b^6 in its upper face. The actuating part C may be either held stationary or revolved by hand 15 independently of the fan-blades, is easily raised and lowered, and remains in its adjusted position. The raising and lowering of the actuating part actually rocks the fan-blades and varies their inclination and operation 20 without retarding the revolution of the frame A, and this result is effected with a minimum degree of friction and effort, owing to the construction and arrangement of the adjacent ends of the spindles or shanks b and 25 the upper end of the actuating part.

The operation of my improved device for controlling the operation of a fan will be readily understood upon reference to the foregoing description and the accompanying 30 drawings, and it will be particularly noted that said device is compact, simple in construction, and consists of a minimum number of parts. It is obvious, however, that the exact detail construction and arrangement 35 of the parts of said device may be more or less varied without departing from the spirit of my invention, and hence I do not herein limit myself to such exact construction and arrangement.

40 Having thus fully described my invention, what I claim as new, and desire to secure by Letters Patent, is—

1. The combination of fan-blades having their adjacent ends provided with spindles or 45 shanks formed with grooves extending outwardly from their axes, and a movable actuating part having engaging faces movable in said grooves, substantially as and for the purpose described.

50 2. The combination of fan-blades having their adjacent ends provided with spindles or shanks formed with grooves extending outwardly from their axes, a movable actuating part having engaging faces movable in said 55 grooves, said actuating part being revolvable independently of the fan-blades, substantially as and for the purpose specified.

3. The combination of fan-blades having their adjacent ends provided with spindles or 60 shanks formed with grooves extending outwardly from their axes, and a movable actuating part provided with a substantially spherical projection movable in said grooves, substantially as and for the purpose specified.

4. The combination of fan-blades having 65 their adjacent ends provided with spindles or shanks formed with grooves extending outwardly from their axes, a movable actuating part having engaging faces movable in said grooves and springs for forcing the spindles 70 or shanks toward the actuating part, substantially as and for the purpose described.

5. The combination of a revoluble supporting-frame, fan-blades having their adjacent ends provided with spindles or shanks journaled in the supporting-frame, said spindles or shanks having their adjacent sides provided with laterally-extending arms or projections formed with grooves extending outwardly from the axes of the spindles or shanks, 80 a movable actuating part having a substantially spherical projection movable in said grooves and springs for forcing the spindles or shanks toward the actuating part, substantially 85 as and for the purpose set forth.

6. The combination of a revoluble supporting-frame, fan-blades having their adjacent ends provided with spindles or shanks journaled in the supporting-frame and formed with grooves extending outwardly from the 90 axes, an actuating part reciprocally movable in the frame and revoluble independently of the fan-blades, said actuating part being provided with a substantially spherical projection movable in said grooves, substantially 95 as and for the purpose described.

7. The combination of fan-blades having their adjacent ends provided with spindles or shanks formed with grooves extending outwardly from their axes, a movable actuating 100 part having engaging faces movable in said grooves, for adjusting the fan-blades, said actuating part being provided with a lengthwise passage a switch for controlling the operation of the fan-blades and a second actuating part 105 movable in the lengthwise passage and connected to the switch, substantially as and for the purpose specified.

8. The combination of fan-blades having their adjacent ends formed with grooves extending outwardly from their axes, a movable actuating part having engaging faces movable in the grooves for adjusting the fan-blades, said actuating part being provided 110 with a lengthwise passage, means for actuating 115 the fan-blades, and a second actuating part movable in the lengthwise passage for controlling the operation of said means, substantially as and for the purpose set forth.

In testimony whereof I have hereunto signed my name, in the presence of two attesting witnesses, at Syracuse, in the county of Onondaga, in the State of New York, this 29th day of May, 1896.

HERMAN B. COLLINS.
